P. A. WAGNER

PILE CUTTING DEVICE

Filed Oct. 18, 1921

Inventor:
Paul A. Wagner,
by his attorney,
Charles R. Searle.

Patented Mar. 27, 1923.

1,450,011

UNITED STATES PATENT OFFICE.

PAUL A. WAGNER, OF JERSEY CITY, NEW JERSEY.

PILE-CUTTING DEVICE.

Application filed October 18, 1921. Serial No. 508,586.

To all whom it may concern:

Be it known that I, PAUL A. WAGNER, a citizen of the United States, residing at Jersey City, in the county of Hudson and State 5 of New Jersey, have invented a certain new and useful Improvement in Pile-Cutting Devices, of which the following is a specification.

The invention relates to mechanism for 10 cutting the rows of loops formed by the loom on pile fabrics, and the main object of the invention is to provide means for guiding the loops to the cutters and presenting them in position for accurate and uniform 15 cutting, and a further object is to provide for severing such pile threads by a shearing cut between two opposed blades whereby all the loops are positively severed along the central line of the row of loops, and the 20 sharpness of the cutting edges of the blades maintained for long periods.

Another important object is to provide such cutting mechanism in compact form for successful operation within the narrow 25 limits afforded by the rows of loops so that a group or series of such cutting mechanisms may be placed side by side to cut the loops of a corresponding series of adjacent rows as they are delivered from the pile wires of 30 the loom.

The invention consists in certain novel features of construction and arrangement by which the above objects are attained, to be hereinafter described and claimed.

The accompanying drawings form a part 35 of this specification and show the invention as it has been carried out in practice with a rotary shearing blade operating in conjunction with a relatively fixed shearing blade.

Figure 1 is a side elevation showing a 40 portion of the carrier, the rotating disk, and its supporting arm.

Figure 2 is a similar view of the opposite side, showing the stationary disk.

Figure 3 is a plan view corresponding to 45 Figure 1.

The remaining figures are on an enlarged scale.

Figure 4 is a vertical section taken on the 50 line 4—4 in Figure 1.

Figure 5 is an elevation showing the outer face of the rotating disk.

Figure 6 is an elevation of the inner face of the stationary disk.

Figure 7 is a horizontal section through 55

the stationary disk and its supporting arm.

Figure 8 is a vertical longitudinal section through a portion of the carrier, showing the disks in elevation.

Similar reference numerals indicate the 60 same parts in all the figures.

The carrier 10 is a thin plate of steel, preferably plane along its lower edge which is extended at the front to form a thin narrow tongue 11 adapted to enter the loops of the 65 pile fabric and guide them to the blades. The upper face of the tongue is inclined upwardly and rearwardly at 12 to open the loops, and from the incline 12 the plate is cut away on a curve at 13.

The tongue 11 has a perforation 14 at its 70 end adapted to join it to a pile wire, not shown, and from a point near the end the upper face of the tongue is provided with an angular groove 15 extending to its junction 75 with the plate and continued upwardly along the curved edge 13 of the latter.

In the plate at the rear are holes 16 adapted to receive bolts or rods, not shown, upon which the carriers are supported on the loom 80 in series, each in line with its row of pile stitches or loops, and separated from each other by distance washers, as will be understood.

On the side faces of the plate 10 are riveted spring-arms 17 and 18 extending forwardly and having openings in their overhung free ends in axial alignment with each other, adapted to receive cylindrical bosses 19 and 20 on the cutters 21 and 22 and support the cutters with liberty to rotate between the arms while lightly pressed together by the spring force exerted by the arms.

In the boss 19 is a square axially located 85 opening 23 extending through the cutter 21 and receiving a square shaft 25 by which the cutters 21 of the series are rotated, and in the boss 20 is a centrally located circular opening 24 slightly larger in diameter than 90 the diagonal of the square shaft 25 which latter extends therethrough and rotates idly therein.

In the spring-arm 18 is a finger 26 formed 105 integrally therewith by suitable dies, extending forwardly and carrying at its free end a rounded pin 27 adapted to engage one of a concentric series of perforations 28 in the cutter 22 and hold it stationary relatively to the rotating cutter 21. By forcing 110

the finger outwardly the cutter 22 may be released and turned to present another perforation 28 to the pin 27 and the cutter thus held in a new position.

- 5 Each cutter is a disk of the same diameter having on its periphery a series of blades in the form of radial angular teeth with sharp outwardly beveled edges by which the cutting is performed through the shearing action of the moving teeth or blades against the stationary teeth or blades. The blades of the rotating cutter or disk 21 are marked 29 and the blades of the stationary cutter or disk 22 are marked 30. Each disk is hollowed or dished on its inner face, as at 31 and 32, to insure the desired shearing contact of the blades under the pressure exerted by the spring-arms 17 and 18.
- 10

The operation is as indicated in Figure 8 20 in which the uncut loops 33 on the ground fabric 34 are fed from the pile wire, not shown, upon the tongue 11 and opened and slightly strained at their upper portions across the groove 15 as they advance upon 25 the inclined portion 12 of the tongue. The loop threads are thus presented successively to the disks and severed in the centre by the shearing action of a moving blade 29 against a fixed blade 30.

- 25 30 The blades extend well into the groove so that the cutting line is about midway between the root and point of the blades and certainty of severance thus assured. When thus cut, the severed ends 35 pass the carrier on each side and move on with the ground fabric 34 as usual.

The shearing cut thus produced by two opposed blades is clean and positive, and as the shearing line is definite and true, uniformity is insured and the quality of the goods greatly improved.

40 A feature of the highest importance is the long service attained without resharpening, due to the shearing action as against 45 any form of knife action either stationary, rotary or oscillatory in each of which the cutting edge is quickly dulled. The stationary disk may be readily advanced to present a new shearing blade and the rotating disk, 50 by reason of its multiplicity of shearing blades, will maintain its sharpness indefinitely.

55 It is preferable with certain classes of goods to revolve the rotating disk in the direction indicated by the arrow in Figure 8, which is the direction of the travel of the fabric, but the rotating disk may be revolved in the opposite direction thus tending to lift the pile thread and present it for shearing to the adjacent stationary blade.

60 Although the invention is shown and described as operating with circular disks armed with peripheral blades, it will be understood that two shearing blades in any

form operating in conjunction with a member having a groove for presenting the pile threads, and performing the shearing operation in such groove, may be substituted for the disks.

65 The device may be used either singly or 70 in groups, suitably equipped, in cutting the pile loops on previously woven pile fabrics independently of the loom.

I claim:—

75 1. In a device of the character set forth, a carrier, a member thereon having a groove, and two opposed cooperating shearing blades mounted coaxially on said carrier and arranged to operate in such groove and sever a pile thread extended across such groove.

80 2. In a device of the character set forth, a carrier, a member thereon having a groove, two opposed cooperating shearing blades mounted coaxially on said carrier and arranged to operate in such groove and sever a pile thread extended across such groove, and means for holding said blades in shearing contact with each other.

85 3. In a device of the character set forth, a carrier, a member thereon having a groove, two opposed cooperating shearing blades mounted coaxially on said carrier and arranged to operate in such groove and sever a pile thread extended across such groove, means for moving one of said blades, and means for holding the other of said blades stationary relatively to said movable blade.

90 4. In a device of the character set forth, a carrier, a member thereon having a groove, two opposed cooperating shearing blades mounted coaxially on said carrier and arranged to operate in such groove and sever a pile thread extended across such groove, means for moving one of said blades, means for holding the other of said blades stationary relatively to said movable blade, and means for holding said blades yieldingly in shearing contact with each other.

95 5. In a device of the character set forth, a carrier, a member thereon having a groove, and two disks mounted on said carrier and having opposed shearing blades arranged to operate in such groove and sever a pile thread extended across such groove.

100 105 6. In a device of the character set forth, a carrier, a member thereon having a groove, two disks mounted on said carrier and having opposed shearing blades arranged to operate in such groove and sever a pile thread extended across such groove, and means for holding said disks yieldingly in shearing contact with each other.

110 115 120 125 7. In a device of the character set forth, a carrier, a member thereon having a groove, two disks mounted on said carrier and having opposed shearing blades arranged to operate in such groove and sever a pile

- thread extended across such groove, means for holding said disks yieldingly in shearing contact with each other, means for rotating one of said disks, and means for holding the other of said disks stationary relatively to said rotatable disk.
8. In a device of the character set forth, a carrier, a member thereon having a groove, two disks mounted on said carrier and having opposed shearing blades arranged to operate in such groove and sever a pile thread extended across such groove, means for rotating one of said disks, and means for holding the other of said disks stationary relatively to said rotatable disk.
9. In a device of the character set forth, a carrier, a tongue adapted to enter the loops of a pile fabric, and having a groove therein, and two opposed disks having shearing blades arranged to operate in such groove and adapted to sever a pile thread extended across such groove.
10. In a device of the character set forth, a carrier, a tongue adapted to enter the loops of a pile fabric, and having a groove therein, two opposed disks having shearing blades arranged to operate in such groove and adapted to sever a pile thread extended across such groove, and means for holding said disks yieldingly in shearing contact with each other.
11. In a device of the character set forth, a carrier, a tongue adapted to enter the loops of a pile fabric, and having a groove therein, two opposed disks having shearing blades arranged to operate in such groove and adapted to sever a pile thread extended across such groove, means for moving one of said disks, and means for holding the other of said disks stationary relatively to said movable disk.
12. In a device of the character set forth, a carrier, a tongue adapted to enter the loops of a pile fabric, and having a groove therein, two opposed disks having shearing blades arranged to operate in such groove and adapted to sever a pile thread extended across such groove, means for moving one of said disks, means for holding the other of said disks stationary relatively to said movable disk, and means for holding said disks yieldingly in shearing contact with each other.
13. In a device of the character set forth, a plate, a tongue thereon having a groove, spring-arms on said plate, and two opposed shearing blades mounted between said arms and arranged to operate in such groove, and held in shearing contact by said arms.
14. In a device of the character set forth, a plate, a tongue thereon having a groove, spring-arms on said plate, two opposed shearing blades mounted between said arms and arranged to operate in such groove, and held in shearing contact by said arms, means for moving one of said blades, and means for holding the other of said blades stationary relatively to said movable blade.
15. In a device of the character set forth, a plate, arms thereon, two disks revolvably mounted between said arms and having peripheral opposed shearing blades, means for rotating one of said disks, and means for holding the other of said disks stationary relatively to said rotatable disk.
16. In a device of the character set forth, a plate, arms on said plate each having an opening in its free end, two disks revolvably mounted between said arms, each having a boss received in such openings and having peripheral opposed shearing blades, a shaft extended through said disks and bosses and arranged to rotate one of said disks, and means on one of said arms for holding the other of said disks against rotation.
17. In a device of the character set forth, a plate, arms on said plate each having an opening in its free end, two disks revolvably mounted between said arms, each having a boss received in such openings and having peripheral opposed shearing blades, a shaft extended through said disks and bosses and arranged to rotate one of said disks, a series of perforations in the other of said disks, a finger on one of said arms, and a pin on said finger adapted to engage either of said perforations.
18. In a device of the character set forth, a plate, a tongue thereon having a groove, spring-arms on said plate each having an opening in its free end, two disks revolvably mounted between said arms, each having a boss received in such openings and having peripheral opposed shearing blades extending into such groove, a shaft extending through said disks and bosses and arranged to rotate one of said disks, a series of perforations in the other of said disks, a spring finger on one of said arms, and a pin on said finger adapted to engage any one of said perforations.

In testimony that I claim the invention above set forth I affix my signature.

PAUL A. WAGNER.
